SELF-CENTERING FEED ROLLS FOR A DOWEL MACHINE OR THE LIKE

Curt G. Joa, Sheboygan Falls, Wis.

Application June 2, 1950, Serial No. 165,828

6 Claims. (Cl. 144—246)

This invention relates to improvements in self-centering feed rolls for a dowel machine or the like.

The stock from which dowels or similar bars are cut is sometimes square in cross section, and sometimes oblong in cross section. Provided the minimum transverse dimension of the oblong piece is equal to or greater than the diameter of the proposed dowel, the oblong piece should be just as acceptable for the manufacture of such a dowel as a piece of square cross section. However, in practice, the feed rolls heretofore used have been adapted to center stock of square cross section only so that a piece of adequate thickness, but of oblong section, would not be centered and would not result in the production of a perfect dowel.

The present invention is based on the discovery of a cross sectional shape of feed roll which is such that a pair of feed rolls embodying the invention will automatically center, without special attention from the operator, any stock of rectangular cross section within its capacity, whether such stock is square or oblong in section. As will be noted from the following disclosure of my invention, these results are achieved by making the respective roll flanges inwardly convex for at least a portion of their radial extent. At their inner margins the faces of the flanges are nearly parallel. Their divergence increases outwardly. Beyond the convex portions, the faces of the flanges may be conical and at right angles to each other.

In the drawings:

Figure 1 is a perspective view of a dowel rod machine equipped with feed rolls in accord with my invention.

Figure 2 is an elevation showing two of my improved feed rolls with a fairly accurately squared piece of rough stock being fed therethrough.

Figure 3 is a view comparable to Figure 2 but showing an inaccurately squared piece of rough stock being fed and centered through my improved rolls.

Figure 4 is an elevation showing two opposed feed rolls made according to the previously known design and showing an accurately sized piece of rough stock being fed therethrough.

Figure 5 is a view comparable to Figure 3 but showing a pair of feed rolls grooved according to previously recognized practices, with an inaccurately sized piece of rough stock being fed off center therethrough.

Figure 6 is a section on line 6—6 of Figure 2 but deleting any portion of rough stock.

Like parts are designated by the same reference characters throughout the several views.

In many machines such as milling machines and wood working machines, it is of greatest importance that rough stock to be fed into the working mechanism shall be centered accurately so that material need not be wasted or so that an excessive amount of stock need not be removed. In Figure 1 I have shown such a machine. It is a wood-working machine for the reception and work operations incident to the feeding of rough stock supposedly square in cross section for the making of a dowel 8. At the input end of the machine are input rolls 9 and at the output

2

end of the machine are output rolls 10 shaped to hold the finished dowel 8. The dowel 8 is circular in cross section and is worked to accurate dimensions by tools operating in the housing 11. These tools are mounted to work accurately with reference to the center of the dowel 8, and it is, of course, necessary to remove rough stock from the rectangular raw material 12 fed into the machine.

Obviously, the ideal rough stock 12 is a piece of wood accurately sized and perfectly square in cross section so that a corner or ridge 13 between faces 14 and 15, and ridge 16 between faces 17 and 18 are straight and are so positioned that a line between them bisects the angles formed by said side surfaces.

Feed rolls for these machines are power operated on their shafts and the shafts and feed rolls have substantially no "endplay." The feed rolls may move equally and oppositely to and from each other, resiliently under control of special mounting means well known in this art. They, therefore, confine the material to be fed and support it along a centered line so far as vertical dimensions are concerned, and my new feed rolls center the material so far as horizontal dimensions are concerned. The trough 7 is merely approximately adjustably positioned and is merely of assistance to the operator feeding long strips of rough stock to the rolls.

According to heretofore known practices and with equipment known to this art, feed rolls 20 and 21 for the dowel machine shown in Figure 1, have been V-grooved as shown in Figures 4 and 5. In a given radial plane, the feed rolls 20 and 21 have had groove surfaces 22 and 23 at right angles to each other so as to fit snugly against surfaces 14 and 15 and against surfaces 17 and 18, respectively, of a perfectly square piece of rough stock. In this position, if the material is accurately squared, the corner 13 and the corner 16 bear deeply and snugly in the angles of the V-groove in the respective rollers, the faces are in full contact with the side walls of the roll grooves, and the rough stock 12 fed into the machine is accurately positioned so that the circumference of the dowel 8, as shown in dotted lines at 24, will fall entirely within the physical structure of the rough stock, leaving no flat surfaces in the finished dowel 8.

As shown in Figure 5 and again referring to prior art V-grooved rolls, if the rough stock 12 be oblong in section the V-grooves of the rolls 20 and 21 receive the rough stock in an off-center position, since the rough stock will tend to center itself upon one of the rolls and will not bear fully into the V-groove of the other roll. The rough stock being thus off-centered is fed to the cutting tools of the machine 11 and the resulting dowel will have a flat side as diagrammatically indicated at 25 in Fig. 5. Thus despite the fact that the rough stock 12 shown in Figure 5 has ample dimensions in both directions to provide the stock to make the full diameter of the dowel 8, the off-center position of the rough stock due to its improper position in the V-groove of roll 21 causes an imperfect product to be made.

My improved feed rolls, as shown in Figures 2 and 3, meet the problems presented above. My feed rolls 30—31 are identical. To accommodate comparable sizes of rough stock 12, they are somewhat wider and larger in diameter than the rolls 20 and 21. The generally V-shaped grooves of my rolls 30 and 31 have outer portions 32 and 33 disposed at an angle of 90 degrees with respect to each other, but in the deeper portions of the groove these surfaces are annularly bulged at 34—35 and contoured as shown in the drawings so that the extreme peak of a ridge 13 or 16 of a piece of raw stock of angular cross section will be received between the bulging contours and will not contact the feed rolls during a feeding operation. In fact only a "line contact" between

the respective bulging surfaces 34 and 35 and the rough stock 13 will prevail, but it will be noted (see Fig. 3) that despite the fact that raw stock 12, between my rolls is not an accurately dimensioned square, it is positively centered and the circle 24 indicating the diameter of the dowel 8 is entirely included within the physical dimensions of the rough stock 12.

It will be further noted with respect to feed rolls in Figs. 2, 3 and 6 that the bulging contours of my feed rolls are radially grooved at 36, so that my rolls may engage the stock with a more positive feeding action. Rough stock 12 of such physical characteristics as wood will be slightly compressed by the rolls in a feeding operation sufficiently so that the rough stock will be engaged in grooves 36 for more positive feeding action. The resilient pressure of the rolls against the stock may be adjusted in the machine for this purpose and, obviously, any marking of the rough stock by the rolls is of no consequence, since this stock adjacent the ridges 13 and 16 is completely removed in the dowel making operation.

My new feed rolls are therefore effective to center the rough stock according to the ridge lines 13 and 16. There is no permissible "riding" of one of these ridges along such a surface as the surface 17 in old style roll 21 and the vertical center line of the rough stock, normal to the axes of the rolls, is brought most closely to the center of the cross section of the rough stock 12.

As is clearly shown in Figs. 2 and 3 the bulging or convex gripping surfaces 34 and 35 are outwardly offset from the frusto-conical surfaces otherwise provided by 30 the outer flange surfaces 32 and 33 respectively. Accordingly, the workpiece 12, as shown in Fig. 3, is gripped only adjacent its diagonally opposed corners to align the center line of the workpiece with the center line of the cutting head of the machine. In this position the work piece is free for self-adjustment relatively without interference by the outer conical flanges 32 and 33 of the rolls.

I claim:

1. A grooved feed roll for stock having a corner ridge to be engaged by the roll, said roll having divergent flanges, the flanges being relatively less sharply divergent at the bottom of the groove and relatively more sharply divergent adjacent the outside of the roll said flanges having inwardly projecting intermediate portions to receive and engage the sides of the corner ridge at points intermediate said less sharply and said more sharply di- 40

vergent portions of the roll flanges, leaving the apex of the ridge projecting between the less sharply divergent flange portions and out of contact therewith.

2. A grooved feed roll having divergent flanges of 5 frusto-conical form near their outer portions and having inner portions of inwardly convex form, at least part of said convex portions being offset from the frusto-conical portions of the flanges whereby to constitute gripping bulges having line contact with work engaged by the 10 roll.

3. The device of claim 2 wherein the inwardly convex portions of said rolls are provided with laterally extending slits.

4. A pair of cooperating feed rolls for feeding and 15 centering polygonal stock having corner ridges, each of said rolls being provided with two opposed annular inwardly bulging and curvilinearly convex work gripping flanges for substantially line contact with opposite faces of the corner ridges of said stock, the stock being engaged at four points by said flanges and self adjusting between the bulging curvilinearly convex surfaces there- 20 of.

5. A pair of opposed feed rolls for guiding and automatically centering angularly ridged stock and feeding such stock to a dowel machine, each of said rolls having divergent flanges with V-shaped grooves therebetween to receive such stock, the respective flanges each having annular inwardly bulging and substantially continuously curvilinearly convex work-gripping surface for at least a portion of its radial extent whereby the convex portions of the respective flanges concurrently engage the sides of ridged stock in substantial line contact with such sides, the ridges being accommodated in the grooves of said rolls, and the stock being self adjusting between the four flanges of the opposed rolls.

6. The feed rolls of claim 5 in which at least one such roll has its respective flanges provided with outwardly extending slits in its convex work-gripping surfaces.
